BOOT HANGER

Chester E. Peck, La Crosse, Wis., and Joseph B. Bambenek, Winona, Minn.; said Bambenek assignor to said Peck

Application December 5, 1941, Serial No. 421,738

4 Claims. (Cl. 211—34)

Our invention provides an extremely simple, low-cost, and highly efficient boot hanger, the word "boot" being used in a liberal sense to include what is sometimes called "shoes," but particularly it is designed as a convenient and efficient device for hanging heavy boots, such as hunters' and lumbermen's boots and rubber boots in position for drying and if exceedingly wet for draining. The improved device, as preferably designed, is made from two pieces of quite stiff 10 resilient wire bent to form boot-receiving U-forks spaced by an intervening reversely U-shaped fork.

The invention in its preferred form is illustrated in the accompanying drawings wherein like characters indicate like parts throughout the several views.

Referring to the drawing:

Fig. 1 is a view in perspective showing a pair of heavy boots applied to and suspended from the hanger, the latter being hung on a transverse rod; and

Fig. 2 is a view in perspective showing the complete hanger on a larger scale than in Fig. 1.

The boot holder or body of the device is made from a single piece of wire 5 bent to form U-shaped boot-receiving forks 6 and 7 and an intervening reversely U-shaped fork 8. The device, as shown, as adapted to be suspended by a hanger rod 9, the upper end of which is shown as bent to form a hook 10 adapting it to be hung on a pole 11 or the like. This hanger rod 9 is vertically extended at a point that is approximately the center of gravity of the hanger and its lower end 12, within the reverse fork 8, is bent forwardly and attached to that portion of the wire that forms the intervening fork 8. The extreme ends of the wire 5 are preferably outwardly bent at 5' to expand the receiving ends of the U-shaped forks 6 and 7. By bending the rod 9 vertically downward instead of vertically upward from the plane of the double U-shaped holder, the latter could be supported by a pedestal.

The spread of the forks 6 and 7 is such that it 45 will engage the inverted boots with considerable

friction just below the soles thereof and thereby hold the boots firmly in the best kind of position for drying and for maintaining good form.

Obviously the device described can be made at 5 small cost and actual use of the device has demonstrated its efficiency.

What we claim is:

1. A boot hanger comprising a horizontally disposed boot holder made from a wire-like rod bent to form a pair of boot-receiving forks connected by a reversely opening intermediate fork, and a supporting rod attached to the intermediate front portion of said holder-forming wire and extended vertically therefrom and having means for securing it to the holder forming wire.
2. A boot hanger comprising a resilient wire-like rod bent to form a pair of horizontally disposed boot-receiving forks connected by a reversely opening intermediate fork, and a supporting rod extended vertically from the central portion of said holder and having one end bent horizontally and attached to the intermediate front portion of said holder-forming rod.
3. A boot hanger comprising a resilient wire-like rod bent to form a pair of horizontally disposed boot-receiving forks connected by a reversely opening intermediate fork, and a hanger rod extended vertically upward from the central portion of said holder and provided at its upper end with a hanger hook, the lower end of said hanger rod being bent horizontally forward within the reversely U-shaped intermediate fork and connected to the intermediate front portion of said wire-forming holder.
4. A boot hanger comprising a boot holder made from a wire-like rod bent to form a pair of horizontally disposed boot-receiving forks connected by a reversely opening intermediate fork, and a supporting rod extended vertically from the central portion of said holder and having a lower portion bent horizontally and attached to the holder forming wire.

CHESTER E. PECK.
